UNITED STATES PATENT OFFICE.

CHARLES KINNEY, OF ELMIRA, NEW YORK, ASSIGNOR OF ONE-HALF TO LOUISE MAY OSTRANDER, OF ELMIRA, NEW YORK.

PLOW.

1,341,182.

Specification of Letters Patent. Patented May 25, 1920.

Application filed August 12, 1919. Serial No. 316,959.

To all whom it may concern:

Be it known that I, CHARLES KINNEY, a citizen of the United States, residing at Elmira, in the county of Chemung and State 5 of New York, have invented certain new and useful Improvements in Plows, of which the following is a specification.

This invention relates to plows and has for an object to provide means for attaching 10 plows to a wheeled vehicle embodying new and improved features of convenience, reliability and economy in operation.

Referring to the accompanying drawings which form a part hereof and on which similar reference characters indicate similar parts,

Figure 1 is a view of the improved plow in side elevation attached to a conventional form of vehicle; and

Fig. 2 is a view of the plow in top plan, likewise attached to a conventional vehicle.

The improved plow which forms the subject matter of this application is disclosed in its generic form in application No.

259,791, filed October 26, 1918. The present application is directed to the plow structure *per se* as distinguished from the tractor structure which forms the subject matter

30 of the application just above mentioned and comprises any convenient or preferred form of vehicular structure disclosed generally by the structure 10. To the structure of

whatever formation are pivoted one or more frames 11 and 12. In the drawings two of

35 these frames have been shown, but it is to be understood that the invention is in no way limited to the number of such frames or plows to be carried thereby but includes the use of a single frame or a multiplicity

40 of frames as the requirements of the work may make necessary. The frame, or frames, is, or are, also pivoted to the vehicular structure in any approved manner. In the

type as shown in the drawings side bars 13

45 are disclosed attached to the axle 14 in any conventional manner and for the purpose of strengthening provided with a rear brace 15. Between the side bars 13 a shaft

16 is secured and upon this shaft 16 the

50 frames 11 and 12 are pivoted as indicated at 17. Thus far the frames 11 and 12 are free to move about their shaft 16. With two

frames 11 and 12, two plows 18 and 19 will

also be employed and connected with the

55 frames 11 and 12 by means of arms 20 and 21

connected respectively with the beams 22 and 23, preferably by pivoting thereto as more particularly indicated at 24 and 25. The arms 20 and 21 are respectively provided with cross bars 26 and 27 the length 60 of which are substantially the transverse dimensions of frames 11 and 12. The cross bars 26 and 27 are provided with rollers 28 which bear upon the top or upper edges of the frames 11 and 12 respectively with 65 keepers 29 disposed beneath the under or lower edges of the frames 11 and 12 to maintain the cross bars 26 in position. It is obvious that by reason of the spaced pivoting of the frames 11 and 12 such frames will be 70 held against lateral swinging action thereby properly positioning the plows 18 and 19 without in any manner interfering with their vertical movements. The plows are preferably connected through their beams 22 75 and 23 with the yoke 30 in any approved manner as by pivoting at 31 and a draw bar 32 is pivoted to the yoke 30 and is extended forward and connected to the draft means disclosed conventionally by the evener 80 33. The manner of connecting the draft means with draw bar 32 forms no limitation of the present invention but preferably is by means of a link 34 extending upwardly to the tongue 35 of the vehicle whereby draft 85 is also applied to the vehicle as well as to the plows to insure simultaneous action.

For the purpose of lifting the plows out of operative position as shown at Fig. 1 a crank shaft 36 is journaled upon the vehicle 90 as indicated at 37 and a lever 38 and segment 39 are employed for applying manual stress thereto in the usual well known manner. The shaft is connected with the plow beams 22 and 23 in any well known manner 95 as by chains 40. A seat 41 is mounted conveniently upon a spring 42 for the use of the operator.

To insure the proper depth of plowing dependence is not placed in any respect upon 100 the vehicular structure but a caster wheel 43 is applied to each of the beams 22 and 23 with the usual and ordinary adjusting means by means of the bar 44. By adjusting the position of the caster wheel 43 relative to 105 the beams the depth of plowing is regulated.

It is obvious in operation the lowering of the plows by manipulation of the lever 38 will bring the plows into contact with the earth in the usual well known manner and 110

the forward movement of the vehicle will cause the plows to enter the earth until they have reached the depth provided by their caster wheel, when they will follow a course 5 corresponding to the surface of the earth. The plows thus mounted are wholly free of the vehicle so far as vertical movement is concerned, but their lateral position is controlled by their frames 11 and 12 which offer 10 no resistance to vertical movement or in any way control the depth but only the width of furrow.

Having thus fully described my said invention, what I claim as new and desire to 15 secure by Letters Patent, is:

1. A plow comprising a vehicular structure, a frame pivoted to the vehicular structure at spaced points and adapted to swing in a vertical plane, a plow beam connected 20 with the frame by means of a sliding engagement, means independent of the frame to raise and lower the plow relative to the vehicular structure, and means to regulate the depth of the plow.
2. A plow comprising a vehicular structure, a frame having spaced bars pivoted at correspondingly spaced points upon the vehicular structure and free to move upon its pivot in a vertical plane, a plow, rollers 30 carried by the plow bearing upon the frame providing means whereby the plow is free to move longitudinally relative to the frame but is laterally restrained thereby, means to raise and lower the plow and connected frame, and means to regulate the depth of the plow.
3. A plow comprising a vehicular structure embodying a frame, an auxiliary frame comprising spaced side bars pivotally connected to the vehicular structure at correspondingly spaced points and adapted to swing in a vertical plane, a plow disposed 40 beneath the auxiliary frame, a cross bar extending beneath the bars of the auxiliary frame, rollers carried by the crossbars movable upon the auxiliary frame, means connecting the cross bar with the plow, means to regulate the depth of the plow independently of the auxiliary frame, and means to 45 apply draft to the plow.
4. A plow comprising a vehicular struc-

ture embodying a frame, an auxiliary frame pivotally connected with the vehicular frame at points and embodying spaced side bars free to move upon its pivot in a vertical plane but restrained from lateral variation, a plow beneath the auxiliary frame, a cross bar extending between the side bars of the auxiliary frame, rollers journaled upon the cross bars and bearing upon the sides of the auxiliary frame, means pivotally connecting the cross bar with the plow, whereby the plow is free to move longitudinally of but restricted laterally relative to the auxiliary frame, means to raise and lower 65 the plow and auxiliary frame relative to the vehicular structure, means to regulate the depth of the plow independently of the vehicular structure, and means to apply draft to the plow.

5. A plow comprising a vehicular structure, a frame pivoted to the vehicular structure at spaced points and adapted to swing in a vertical plane, a plow beam connected 70 with the frame by means of a sliding engagement, means independent of the frame to raise and lower the plow relative to the vehicular structure, means to apply draft to the plow independently of the raising and lowering means, and means to regulate the 75 depth of the plow.

6. A plow comprising a vehicular structure, a frame having spaced bars pivoted at correspondingly spaced points upon the vehicle structure and free to move upon its 80 pivots in a vertical plane, a plow, rollers carried by the plow bearing upon the frame providing means whereby the plow is free to move longitudinally relative to the frame but is laterally restrained thereby, means to raise and lower the plow and connected frame, means to apply draft to the plow independently of the raising and lowering means, and means to regulate the depth 85 of the plow.

In witness whereof, I have hereunto set my hand and seal at Elmira, New York, this 8th day of August, A. D. nineteen hundred and nineteen.

CHARLES KINNEY. [L. S.]
